OIL CAN

Filed July 26, 1930

UNITED STATES PATENT OFFICE

WILLIAM T. FAUX, OF SANTA BARBARA, CALIFORNIA

OIL CAN

Application filed July 26, 1930. Serial No. 470,790.

This invention relates to improvements in containers especially designed to hold such contents as oil, molasses and similar viscous fluids.

55 One of the objects of this invention is to provide a simple, efficient and inexpensive oil can equipped with a movable spout and so shaped and constructed that the spout may readily and quickly be caused to become entirely located inside the can so no part of its main length projects outside the can.

10 Another object of this invention is to provide a combination spout and valve so arranged and construction that in one position it is completely housed in the can and its valve is shut off, and in another position it projects below the can and then its valve is automatically opened and the contents of the can may be drained off thru the spout. A

15 further purpose of this invention is to provide in conjunction with an oil can or the like an upright discharge tube extending extensively with the length of the can and opening out from the bottom of the can, there being a tubular spout telescoping slidably in said tube and designed to be manually moved out of the lowermost end of the can, means being provided whereby when the tubular spout shall have been caused to project below the can the line of flow of the contents of the can will be into the spout and out of the can.

20 A still further feature of this invention is to provide an oil can with an internal discharge tube having a port at its lower portion, a tubular feed spout slidably mounted in the tube and having a port normally closed by the tube when the spout is out of projecting relation with respect to the can, but caused to be uncovered when the spout has been lowered to project below the can.

25 In carrying out my invention I also provide in conjunction with the telescoping projecting spout a handle slidably projecting outside of the can where same may be grasped hold of to move the spout downwardly in the can.

30 A further object of this invention is to provide a bottom on the can raised above its lowermost end and made dish-shaped and

sloping so that it will conduct and direct oil into the port formed in the discharge tube from all directions to assure that all the contents of the can will be drained out of the movable spout.

55 A final object of this invention is to frictionally retard the descent of the tubular spout by supplying spring pressure against the adjustable spout.

60 With the above and other objects in view my invention consists in the arrangement, combination and details of construction disclosed in the drawing and specification, and then more particularly pointed out in the appended claim.

65 In the drawing wherein similar reference characters designate similar parts throughout the several views,

70 Figure 1 is a top plan view of my invention,

75 Figure 2 is a vertical elevation thereof,

Figure 3 is a side elevation of my invention,

Figure 4 is a fragmental sectional view of 75 the lower section of the oil can,

Figure 5 is a cross sectional view of the can taken on line A—A of Figure 2,

Figure 6 is a bottom plan view of the invention, and

80 Figure 7 is a vertical elevation of the invention showing the handle.

85 In the drawing, wherein similar reference characters designate similar parts throughout the respective views, and which are merely illustrative of my invention, 10 designates the oil can proper which will be made of any suitable material such as of metal being hollowed out and made of durable formation.

90 At its upper mouth end an annular bead is returned upon the edge of the can as at 14

providing an inner annular chamber or space 15 so where only a small portion of the oil

remains in the can and the can is inverted it will run as a film upon the side of the can and

find lodgment in the space 15 so as not to run out and reach the bead 14 proper. There is

95 a sheet metal handle provided upon the can consisting of the flat portion 11 having the upper curved portion and the lower curved 100

portion 12, the latter portions being welded or otherwise secured fixedly upon the can.

For the purpose of reinforcing the can and preventing the too ready buckling thereof I provide at the lower portion of the can an annular pressed-out rib 16, while the lowermost end of the can 10 may bulge out annularly as at 17 for reinforcing purposes as well. The bottom wall 18 of the can is raised above the lowermost end of the can and is formed preferably dish-shaped and made to incline so as to slope gradually for the major portion and radius of the can and made to slope precipitately as at 19 in the minor radius or in the immediate vicinity of the discharge tube now to be described.

That portion of the can below the bottom wall is designated 20 while inside of the can this portion constitutes a base compartment 21. I provide a tubular spout 22 made substantially of the length of the can proper and formed laterally at its upper end is an elongated opening 23. The tubular spout 22 is slidably and non-rotatably and telescopically mounted in the discharge tube 24 which also extends coextensively of the can. The discharge tube 24 is a rigid hollow body which is closed at its upper end as at 34 and which opens out at its lowermost end from the bottom of the can 10. This discharge tube may either be formed or welded upon the inner face of the shell of the can as shown in Figure 5, or else it may be a separate tube operatively secured to said wall as shown in Figure 6. This discharge tube is formed with a dish-shaped bottom wall 18 and is provided with a lateral port 26 of a length slightly less than that of the passage or opening 23. Normally, that is, when the tubular spout is completely housed in the tube 24 in which it is guided for movement its elongated passage will be closed or covered by the tube 24, while the port of tube 24 will be closed, as shown in Figure 2, by the tubular spout 22.

It will also be seen that there is an elongated slot formed upon the shell of the can as at 29' and a similar slot 30' may be formed in the discharge tube 24, both slots registering. In Figure 2 the discharge tube is formed or welded directly on the shell of the can so that the slot need only be formed upon the shell alone.

At the upper end of the tubular spout a handle 29 in the form of a ring or otherwise is mounted. This ring has a strap 27 secured by the fasteners 28 directly to the spout, the handle slidably projecting outside the can as shown in Figure 2. When the spout engages the upper closed end 34 of this discharge tube the passage 23 is out of registration with port 26 and the handle 29 for slidably actuating the tubular spout is at the upper end of the can; the lowermost end of the tube 24 projects into chamber 21 and holds the lowermost portion of the slidable

tubular spout 22 therein, and this spout also opens out of the lower end of the can.

In order to retard the too free descent or ascent of the tubular spout 22 in the casing or tube 24, I provide or may provide a brake in the form of a spring finger now to be described. Reference being made to Figure 4, it will be seen that the tube 24 is formed at its lower end with a notch 33. The curved terminal 32 of a flat spring arm 30 is designed to exert a spring pressure against the lowermost end of the spout 22, this spring arm projecting into the notch 33 for this purpose and secured at its inner end 31 fixedly to the tube 24. As the spout is moved in the tube 24 this spring arm 32 applies sufficient friction to allow the spout to move slowly in and out of the tube 24.

It will now be seen that when it is desired to operate the tubular spout the handle 29 is taken hold of by the operator and the spout slid as far down in the tube 24 as it can go, until the handle 29, shown in dotted lines in Figure 2, comes to the limit of the slot 29' at its lowermost end; the lowermost portion of the tubular spout 22 is now caused to project below the bottom of the can as shown in dotted lines in Figure 2. When the tubular spout thus comes to rest it will be readily seen that the opening 23 in the tube registers or communicates with the port 26 of the tube 24 so both ports are now open to the line of flow of the contents of the can, the sloping bottom 18 of this can assisting in conducting the oil thru the port, 26, opening 23, and thus causes the oil to come out of the lower end of the spout into whatever vessel the spout empties into. The operator does not touch the spout ordinarily and thus his hands do not become besmirched with oil. I do not limit myself to the exact details of construction but claim all variations within the purview of the claim.

What I desire to claim and secure by Letters Patent is:—

In a device as described the combination of an oil can formed upon one side with an elongated slot, a tubular casing secured against the inner circumference of the can so as to bear in tight contact with the slotted portion thereof, laterally of the medial part of the can, said tubular casing extending practically the full length of the can, being closed at its upper end and open at its lower end, a slide tube snugly and frictionally telescoping in said casing and of a co-extensive length therewith, an eyelet-shaped handle carried by the upper end of the tube, said casing having a slot thru which the handle slidably projects, as the tube is moved downwardly so that its open lower end may project below the can and provide an oil-pouring spout, a floor extending transversely in said can above the lower end thereof, and inclining downwardly towards said casing,

said casing being formed with a lateral opening in a plane with said floor, said tube being also formed with a lateral opening of a length greater than the lateral opening of the casing, the bottom edge of the two slots being located at such a point that when the handle rests thereupon, when the tube is pushed downwardly, the upper part of the lateral opening of the tube will register with the opening of the casing while the lower part thereof will be below the floor of the can.

10 In witness whereof he has hereunder set his hand this 5th day of July, 1930.

15 WILLIAM T. FAUX.
